UNITED STATES PATENT OFFICE.

THOMAS J. KEEPING, OF LOS ANGELES, CALIFORNIA.

LAMP-SHADE-DELIVERY BOX.

Application filed September 19, 1921. Serial No. 501,738.

To all whom it may concern:

Be it known that I, THOMAS J. KEEPING, a citizen of Great Britain, residing at Los Angeles, in the county of Los Angeles and 5 State of California, have invented certain new and useful Improvements in Lamp-Shade-Delivery Boxes, of which the following is a specification.

This invention relates to delivery boxes 10 for ornamental lamp shades.

The object of the invention is to provide a box of this character for use by lamp shade stores for delivering ornamental or other frangible shades of this character, 15 and which is so constructed as to prevent all possibility of a shade being broken or in any way damaged and which will also protect it from the weather.

With these and other objects in view, the 20 invention consists in certain novel features of construction as hereinafter shown, described and claimed.

In the accompanying drawings:

Figure 1 represents a longitudinal section 25 of a box constructed in accordance with this invention.

Fig. 2 is a horizontal section taken on the line 2—2 of Fig. 1.

Fig. 3 is a top plan view of the stand employed in connection with this box, the supporting frame being removed.

Fig. 4 is a side elevation thereof, with the supporting base shown in section; and

Fig. 5 is a vertical section taken on the 35 line 5—5 of Fig. 3.

Department and other stores handling ornamental lamp shades frequently have large numbers broken or damaged in delivery, and it is to overcome this expensive 40 feature of the lamp shade business that this invention is designed.

In the embodiment illustrated a casing or 45 box 1 is shown, which may be of any desired configuration, being here shown square.

This box is equipped with a hinged top 2, having any suitable means for securing it in closed position as shown at 3.

Removably mounted within the casing or 50 box 1 is a supporting standard 5, composed of wood or any suitable material, and centrally disposed on the inner face of the bottom 4 of the box, being here shown held engaged therewith by a screw 6 which extends

in through the bottom of the box having the head thereof countersunk as is shown 55 clearly in Fig. 1.

As shown this post 5 tapers toward its upper end, and is equipped with a removable section 7 held in operative engagement with the post 5 by a threaded bolt 8, which 60 extends longitudinally into the post from its upper end, and is equipped with a wing nut 9, for securing to the post the shade supporting frame or frames, presently to be 65 described.

The shade supporting frame is shown at 70 10, any desired number of which may be employed, said frames being separated by the sections 7 which operate as spacers and fasteners for the frames.

Each of these shade supporting frames 75 10 is composed of a plurality of wire fingers 11, bent into the form of a bow or to correspond to the shape of a lamp shade, any desired number of these fingers being employed, eleven being here shown and connected by an annular member 12, a smaller ring 13 connects the inner or upper ends of the fingers 11, as is shown clearly in Figs. 1 and 2, and a centrally apertured 80 plate or washer 14 is arranged within said ring 13, and adapted to be inserted on the bolt 8, and which is held engaged with the post 5 by means of the said wing nut 9 and the washer 15 arranged between said nut 85 and the plate 14 as is shown clearly in Fig. 1.

The inner shade supporting member 10^a is exactly like the outer member 10, and is held spaced therefrom by the post section 90 7. It is of course to be understood that when more than two of the shade supports or frames 10 are employed, an additional number of removable sections 7 are also used, such sections operating as spacers to 95 hold the supports 10 in spaced relation, as is shown clearly in Fig. 1.

In the use of this delivery box, the posts 5 having been mounted within the casing 1, the shades to be delivered are mounted 100 respectively on the supporting frames 10, 10^a, it being obvious that the wing nut 9 is removed together with the removable section 7 for the insertion of the shade on the innermost frame member 10^a, then the removable section 7 is replaced and the outer 105

face support 10 is applied to the bolt 8 and after placing a shade on this holder the wing nut 9 is screwed home and the shade will be securely held against wobbling and all possible injury.

These holders 10, 10^a are of course positioned in upright relation when being transported, so that the shades mounted on the holders will hang properly and prevent possibility of them becoming entangled with each other and being thereby torn or otherwise injured.

The fingers 11 are preferably of a length corresponding to the depth of the shade and the holders 10 and 10^a correspond approximately in shape to the shape of the shade to be carried thereby, so that said fingers or ribs 11 will form a rest for the shade, and be held against wobbling.

The post 5 is braced by a plurality of inclined bars 5^a, which are also detachably engaged with the bottom 4 of the casing and as shown are detachably connected with the post, so that the device may readily be disassembled when for any reason it is desired to remove the stand or support from the casing.

These delivery boxes are to be retained as the property of the store selling the lamp shade, and are retained by the driver or other employee delivering the shade, so that they may be used over and over again, indefinitely.

The preferred embodiment of the invention is disclosed in the drawings and set forth in the specification, but it will be understood that any modifications within the scope of the claimed invention may be made in the construction without departing from

the principle of the invention or sacrificing any of its advantages.

What I claim is:

1. A delivery box of the class described, comprising a closed casing, having a shade stand or support mounted therein, and composed of nested members constituting a plural support for a plurality of lamp shades.

2. A delivery box of the class described comprising a closed casing, a post mounted in said casing, and a plurality of nested bow shaped shade supports removably mounted on said post.

3. A delivery box of the class described comprising a closed casing, a post mounted therein, a shade supporting frame carried by said post, and composed of a plurality of wire fingers, connected by annular members and means for detachably mounting said support on said post.

4. A delivery box of the class described comprising a closed casing, a post removably mounted in said casing, a removable section carried by said post, and a plurality of lamp shade supporting frames mounted on the post and separated from each other by said removable section.

5. A delivery box of the class described comprising a closed casing, a post mounted in said casing, a threaded bolt carried by the upper end of said post and extending longitudinally into it, a wing nut on said bolt, and a bow shaped lamp shade supporting frame mounted on said bolt and secured by said nut.

In testimony whereof I affix my signature hereto.

THOMAS J. KEEPING.
